UNITED STATES PATENT OFFICE.

FRANCIS NESBITT POIGNAND, OF WESTFIELD, NEW JERSEY, ASSIGNEE, BY MESNE ASSIGNMENTS, TO SUPER-GAS CORPORATION, OF WILMINGTON, DELAWARE, A CORPORATION OF DELAWARE.

DUPLEX THROTTLE VALVE.

Application filed April 20, 1926. Serial No. 103,396.

The main object of the present invention is to provide an efficient and reliable valve device adapted to automatically maintain a desired fluid pressure by admitting fluid from a low pressure source as it is needed and by admitting fluid from a high pressure source when the pressure of the fluid from the low pressure source falls below that which it is required to maintain. 5

Another object of the invention is to provide an automatic duplex throttle valve adapted to automatically maintain a flow of steam at a predetermined, low pressure, and to receive steam for this purpose from a low pressure source and from a high pressure source. Under normal conditions the valve is adapted to admit steam from the low pressure source. If the pressure from this low pressure source drops below a predetermined point the valve is adapted to automatically admit sufficient high pressure steam to maintain the desired low pressure flow. The valve is capable of adjustment for maintaining different degrees of pressure. 15

A further object of the invention is to provide a duplex pressure maintaining valve which is adapted to be easily adjusted for maintaining different degrees of fluid pressure. 20

Other objects of the invention will appear hereinafter.

In the drawings:

Fig. 1 is a sectional view of the valve device showing the parts in a position to admit low pressure fluid;

Fig. 2 a sectional view showing the operation of the valve device to shut off the fluid delivery;

Fig. 3 a sectional view of the valve device showing the parts in position to admit high pressure fluid; and

Fig. 4 a top plan view of the valve device.

Referring to the various parts by numbers, the valve device comprises a casing 1, formed with an inlet chamber 2 and an outlet chamber 3. The casing is formed at one side with a low pressure inlet 4 which leads into the chamber 2. This inlet is adapted to be connected to a source of steam or other fluid under low pressure. At its opposite side the casing is formed with an outlet 5 which leads from the chamber 3. The outlet is adapted to be connected with the point at which the constant pressure is required. 25

Above the inlet chamber 2 the valve casing is formed with a vertically disposed cylinder 6 and with a passage 7 leading downwardly from the bottom of said cylinder to the chamber 2. An inlet opening 8 is formed in one side of the cylinder 6 midway the height thereof. To the casing is connected a supply pipe 9 which leads into the opening 8. This pipe connects with a source of steam or other fluid under high pressure. Above the outlet chamber 3 the valve casing is formed with a vertically disposed cylinder 10 of much less height than the cylinder 6. The lower end of the cylinder 10 opens directly into the chamber 3 and its upper end is closed by an end plate 11. The upper end of the larger cylinder 6 is closed by an elongated horizontal plate 12 which is removably secured at one end to the upper end of the cylinder 6 by bolts or screws 13, and adjacent its opposite end is removably secured by bolts 14 to an upstanding bracket 15 formed upon the valve casing. 30

A feed valve 16 is provided for controlling communication between the inlet chamber 2 and the outlet chamber 3. The valve 16 is in the form of a hollow cylinder open at both ends and formed with outwardly extending peripheral flanges 17 at its ends. 35

The valve is disposed vertically within the casing, and the casing is formed, between the chambers 2 and 3, with two horizontal walls 18 and 19 spaced apart vertically a distance equal to the distance between the valve flanges 17. The walls 18 and 19 are formed with openings adapted to slidably receive these flanges and guide them for vertical movement. Formed upon the valve 16, below the flanges 17 are guide ribs 20 adapted to engage in the guide openings of the walls 18 and 19 when the valve is moved upwardly to carry the flanges out of said openings. In this position of the valve the inlet chamber 2 is placed in communication with the outlet chamber 3 and the valve is said to be open. When the valve is in its lowermost position the flanges 17 close the openings in the walls 18 and 19 to shut off communication between the chambers 2 and 3 and the valve is said to be closed. The valve is centrally formed with webs 21 which support an operating stem 22. The stem extends upwardly 40

through an opening in a horizontal wall 23 formed in the casing and spaced above the wall 18. The upper end of the stem has a pin-and-slot pivotal connection with a lever 24 located within the outlet chamber 3 and fulcrumed upon an ear 25 carried by the casing. The opposite end of the lever 24 has a pin-and-slot pivotal connection with an ear 26 which depends from a pressure control 10 piston 27 fitted within the short cylinder 10. The arms of the lever are of equal length.

Within the cylinder 6 is a high pressure control valve 28 formed with spaced piston heads 29 which slidably fit within the cylinder. Between the under side of the valve 28 and the bottom wall of the cylinder is a coiled compression spring 30 which tends to force the valve upwardly against the upper end plate 12 of the cylinder. The valve is 20 so proportioned that in all of its vertical positions the space between its piston heads 29 will be in communication with the high pressure inlet 8. The valve casing 1 is formed in one side with a passage 31. This 25 passage leads from the cylinder 6, at a point below the inlet 8, downwardly to the space between the horizontal walls 18 and 23, above the valve 16. In the upper position of the valve 28 the upper end of the passage 31 is 30 below the lower piston head of the valve and is uncovered. In the lowermost position of the valve 28 its lower piston head is disposed below the entrance of the passage 31 and said 35 passage is then connected to the inlet passage 8 through the space between the piston heads 28. This is the open position of the valve.

The piston 27 is provided with an operating stem 32 which extends upwardly through an opening in the cylinder end 11 and through a guide opening in the plate 12. The high pressure valve 28 is also provided with an operating stem 33 which extends upwardly through an opening in the plate 12. Formed upon the plate 12, midway between the stems 32 and 33, are two spaced upstanding ears 34 having vertically extending slots 35. A lever 36 is located between the ears 34 and fulcrumed upon a pin 37 extending between the ears and having its ends slidably fitted in the slots 35. The arms of the lever 36 are of equal length and its opposite ends bear respectively upon the stems 32 and 33. A lever 38 is slidably and pivotally connected to the pin 37. This lever is forked at one end to straddle the two ears 34 and the legs 39 of the fork are formed with longitudinally extending slots 40 through which the projecting ends of the pin 37 extend. The free ends of the fork arms 39 are pivoted or fulcrumed as at 41 to an adjustable cross head 42. The cross head extends transversely across the upper surface of the plate 12 and its opposite ends are slidably supported by guide rods 43. The rods 43 are rigidly supported slightly elevated above

the plate 12 by upstanding ears 44 and by a transversely extending bracket 45 carried by the plate 12. An adjusting screw stem 46 extends inwardly from the bracket 45 parallel to the guide rods 43 and threaded through the cross head 42. The outer end of the adjusting screw is provided with a fork 47 to which an operating member may be connected. The screw is mounted to turn within a bearing opening in the bracket 45 but is held against endwise movement. The free end of the lever 38 extends outwardly from the fork beyond the valve casing and has a weight 47 mounted upon it.

A check valve 49 for closing the low pressure inlet is slidably mounted upon a stem 50 supported by the casing. This check valve is normally held open by a spring 51, and when closed against the resistance of the spring it is adapted to seat against the end of a bushing 52 fitted within the inlet. The valve casing is enlarged adjacent the inlet to accommodate the check valve and the lower side of said enlarged portion is formed with a drain opening normally closed by a threaded plug 53. Directly beneath the valve 16 the lower wall of the valve casing is formed with an opening through which said valve is inserted. This opening is closed by a removal plate. Tapped into a threaded opening in the casing located just above the plate 54 is a nozzle 55 normally closed by a cap 56. In case of a failure in the supply of fluid through the inlet 4 and the pipe 9, a supply may be admitted from another source through this nozzle.

Fig. 1 of the drawings shows the positions of the various parts when the check valve 49 and the feed valve are both open to admit fluid at low pressure through the inlet 4; into the chamber 2, past the feed valve, into the chamber 5 and thence to the point where the fluid is needed. The hollow valve 16, the passages 7 and 31 and the space within the cylinder 6 below the valve 28, all form in effect part of the inlet chamber 2. The high pressure valve 28 is therefore always subject to the pressure in the chamber 2. In Fig. 1, this pressure, combined with the pressure of the spring 30, is holding the high pressure valve in its upper or closed position against the resistance of the weight 48. The piston 27 which operates the feed valve is held in its lower position by the weight 48 acting through the levers 38 and 36 and the stem 32, and the feed valve is held open. When sufficient pressure builds up in the chamber 3 to overcome the resistance of the weight the piston 27 is forced up to rock the lever 24 and move the feed valve 16 down to closed position as shown in Fig. 2. Upon a drop in pressure within the chamber 3 the weight 48 will automatically again move the piston down to reopen the feed valve 16 and re-build the pressure.

If the pressure supplied through the low pressure inlet 4 should drop below the pressure required in chamber 3, the weight 48 will overcome the diminished pressure in the cylinder 6 and the resistance of the spring 30 and force the high pressure valve 28 down to open position as shown in Fig. 3. High pressure fluid then enters the cylinder 6, between the piston heads 29 of the valve, flows through the passage 31 into the chamber 2 and past the feed valve 16 to the constant pressure chamber 3. When the pressure builds up sufficiently the piston 27 closes the feed valve against the weight resistance and retains the high pressure in the chamber 2. When the high pressure fluid first enters the chamber 2 it immediately closes the check valve 49 and prevents the fluid from escaping through the low pressure inlet 4.

The weight 48 and the adjustment of the lever 38 determine the degree of pressure maintained in the chamber 3. By shifting the cross head 42 inwardly the lever 38 is moved longitudinally and its fulcrum is moved inwardly toward the pin 37, which is the point of load application. The mechanical advantage of the weight is increased by this adjustment and it will resist a greater fluid pressure upon the valves. To maintain a lower pressure the cross head 42 is moved outwardly to slide the lever over the pin and shift the fulcrum away from the point of load application. The levers are so designed and arranged as to render it extremely easy to make these adjustments. The adjustment may be made from a point located a considerable distance from the valve by means of a reach rod or other connection with the adjusting screw 46 of the fulcrum cross head.

What I claim is:

1. A valve casing formed with an inlet chamber and an outlet chamber, the inlet chamber being provided with a low-pressure inlet and with a high-pressure inlet; a feed valve controlling communication between said two chambers; means operating to close the feed valve when a predetermined degree of fluid pressure is in the outlet chamber; a high-pressure valve controlling communication between the high-pressure inlet and the inlet chamber; and means to impose equal pressures on the feed valve and on the high-pressure valve tending to open said valves, said pressure-imposing means opening the high-pressure valve and the feed valve when the pressures in the two chambers fall below the valve-opening pressure.

2. A valve casing formed with an inlet chamber and an outlet chamber, the inlet chamber being provided with a low-pressure inlet and with a high-pressure inlet; a feed valve controlling communication between

said two chambers; means operating to close the feed valve when a predetermined degree of fluid pressure is in the outlet chamber; a high-pressure valve controlling communication between the high-pressure inlet and the inlet chamber; means to impose equal pressures on the feed valve and on the high-pressure valve tending to open said valves, said pressure-imposing means opening the high-pressure valve and the feed valve when the pressures in the two chambers fall below the valve-opening pressure; and adjustable means for varying the valve-opening pressure.

3. A valve casing formed with an inlet chamber and an outlet chamber the inlet chamber being provided with a low pressure fluid inlet; a feed valve controlling communication between said two chambers, a high pressure fluid connection; a valve adapted to be opened to supply high pressure fluid from said connection to the outlet chamber; means to automatically close the feed valve when a predetermined fluid pressure is built up in the outlet chamber; weighted means tending to open both of said valves, the opening of the valves being resisted by the fluid pressure in the valve casing; and a check valve adapted to prevent the escape of high pressure fluid through the low pressure inlet, the said weighted means being adapted to open the high pressure valve when the pressure in the outlet chamber falls below the pressure at which the feed valve is opened.

4. A valve casing formed with an inlet chamber and an outlet chamber, the inlet chamber being provided with a low pressure inlet; a normally open feed valve controlling communication between said two chambers; means operated by the fluid pressure in the outlet chamber to automatically close the feed valve when said pressure reaches a certain degree; a high pressure fluid supply connection; a high pressure valve controlling communication between said supply connection and the inlet chamber; means tending constantly to open both of said valves, the opening of the valves being resisted by the fluid pressure in the inlet and outlet chambers and the said valve opening means being adapted to open the high pressure valve when the fluid pressure in the inlet chamber falls below a certain point; and a check valve adapted to prevent the escape of high pressure fluid through the low pressure inlet.

5. A valve casing formed with an inlet chamber and an outlet chamber, the inlet chamber being provided with a low pressure fluid inlet; a feed valve to control communication between said two chambers; means operated by the fluid pressure in the outlet chamber to close the said feed valve when said pressure reaches a certain point;

4

a high pressure fluid supply connection; a high pressure valve adapted to be opened to supply fluid from said connection to the outlet chamber; a weighted lever having a shiftable fulcrum; operative connections between the lever and the said two valves adapted to permit the valves to open and close independently of each other, the weighted lever tending constantly to open the valves through said operative connections; and means to shift the fulcrum of the lever to vary its valve opening force, the opening of the valves by the lever being resisted by the fluid pressure in the valve casing and the lever being adapted to open the high pressure valve when the pressure in the outlet chamber falls a predetermined degree below the pressure at which the feed valve is opened; and means adapted to prevent an escape of high pressure fluid through the low pressure inlet.

6. A valve casing; two valves within said casing adapted to control the admission of fluid from different sources and provided with upwardly extending operating stems; a floating lever of the first class having its opposite ends operatively engaging said valve stems; a fulcrum mounting for the lever adapted to permit vertical shifting of the fulcrum; a valve-opening lever of the second class; a shiftable fulcrum mounting for the valve opening lever; a load connection between the valve-opening lever and the fulcrum of the floating lever adapted to permit the valve-opening lever to slide longitudinally relatively to said fulcrum; a weight carried by the free end of the valve opening lever; and adjustment means to shift the fulcrum of the valve opening lever and slide the lever across the fulcrum of the floating lever to vary the mechanical advantage of the weight, the said weight tending to depress the two levers against the resistance of fluid pressure within the valve casing and the floating lever adapting said valves to be opened independently of each other against the weight resistance.

7. A valve casing formed with an inlet chamber and an outlet chamber, the inlet chamber being provided with a low-pressure inlet and with a high-pressure inlet; a feed valve controlling communication between said two chambers; means operating to close the feed valve when a predetermined degree of fluid pressure is in the outlet chamber; a high-pressure valve controlling communication between the high-pressure inlet and the inlet chamber; and means to impose equal pressures on the feed valve and on the high-pressure valve tending to open said valves, the pressure tending to open the feed valve being opposed by the pressure in the outlet chamber and the pressure tending to open the high-pressure valve being opposed by the pressure in the inlet chamber.

chamber, said pressure-imposing means opening the feed valve when the pressure in the outlet chamber is below the valve-opening pressure and opening the high-pressure valve when the pressure in the inlet chamber is below the valve-opening pressure.

8. A valve casing formed with an inlet chamber and an outlet chamber, the inlet chamber being provided with a low-pressure inlet; and with a high-pressure inlet; a feed valve controlling communication between said two chambers; means operating to close the feed valve when a predetermined degree of fluid pressure is in the outlet chamber; a high-pressure valve controlling communication between the high-pressure inlet and the inlet chamber; and means to impose pressures on the feed valve and on the high-pressure valve tending to open said valves, the pressure tending to open the feed valve being opposed by the pressure in the outlet chamber and the pressure tending to open the high-pressure valve being opposed by the pressure in the inlet chamber, said pressure-imposing means opening the feed valve when the pressure in the outlet chamber is below the valve-opening pressure and opening the high-pressure valve when the pressure in the inlet chamber is below the valve-opening pressure.

9. A valve casing formed with an inlet chamber and an outlet chamber, the inlet chamber being provided with a low-pressure inlet and with a high-pressure inlet; a feed valve controlling communication between said two chambers; means operating to close the feed valve when a predetermined degree of fluid pressure is in the outlet chamber; a high-pressure valve controlling communication between the high-pressure inlet and the inlet chamber; means to impose equal pressures on the feed valve and on the high-pressure valve tending to open said valves, the pressure tending to open the feed valve being opposed by the pressure in the outlet chamber and the pressure tending to open the high-pressure valve being opposed by the pressure in the inlet chamber, said pressure-imposing means opening the feed valve when the pressure in the outlet chamber is below the valve-opening pressure and opening the high-pressure valve when the pressure in the inlet chamber is below the valve-opening pressure; and adjustable means for varying the valve-opening pressure.

10. A valve casing formed with an inlet chamber and an outlet chamber, the inlet chamber being provided with a low-pressure inlet and with a high-pressure inlet; a feed valve controlling communication between said two chambers; means operating to close the feed valve when a predetermined degree of fluid pressure is in the outlet chamber;

a high-pressure valve controlling communication between the high pressure inlet and the inlet chamber; means to impose equal pressures on the feed valve and on the high-pressure valve tending to open said valves, the pressure tending to open the feed valve being opposed by the pressure in the outlet chamber and the pressure tending to open the high-pressure valve being opposed by the pressure in the inlet chamber, said pressure-imposing means opening the feed valve when the pressure in the outlet chamber

is below the valve-opening pressure and opening the high-pressure valve when the pressure in the inlet chamber is below the valve-opening pressure; and means whereby the valves may move to open and closed positions independently of each other and in response to variations of pressures in the said two chambers.

20 In testimony whereof I hereunto affix my signature.

FRANCIS NESBITT POIGNAND.
